UNITED STATES PATENT OFFICE.

HAROLD PEARSON HIRD, OF DEWSBURY, ENGLAND.

STILL.

1,368,149.

Specification of Letters Patent. Patented Feb. 8, 1921.

Application filed June 27, 1919. Serial No. 307,094.

To all whom it may concern:

Be it known that I, HAROLD PEARSON HIRD, a subject of the King of Great Britain, and a resident of "Moor End," Dewsbury Moor, Dewsbury, England, have invented a new and Improved Still, of which the following is a full, clear, and exact description.

This invention relates to stills, and has reference more particularly to a still adapted for the manufacture of pitch carbon from coal tar pitch, and the like.

An object of the invention is to provide a still particularly adapted for the production of pitch carbon from coal tar pitch and similar substances, which is simple and compact in form, in the operation of which heat can be most effectively applied to the material undergoing distillation, which is so constructed that the material can be easily introduced into the still, and from which the resulting residue can be readily and quickly removed.

A further object of the invention is to provide a still which can be inexpensively produced, which can be readily set up or dismantled, and in which the possibility of accidental escape of the material undergoing distillation is obviated.

30 A still further object of the invention is to provide a still for the purpose specified, in which the body of the still consists of a standardized and easily procurable element such as a cast-iron pipe elbow.

35 The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a partial, longitudinal section of a still constituting an embodiment of my invention;

Fig. 2 is a plan view of one end of the still;

Fig. 3 is a transverse section on the line 50 3—3 of Fig. 2;

Fig. 4 is a fragmentary side elevation showing certain details of construction;

Fig. 5 is a diagrammatic outline in plan view, of the surface of the body of material undergoing distillation in the still; 55

Fig. 6 is a reduced, transverse section on the line 6—6 of Fig. 1;

Fig. 7 is a reduced, transverse section on the line 7—7 of Fig. 1;

Fig. 8 is a view similar to Fig. 1, of a 60 modified form of the still;

Fig. 9 is a transverse section on the line 9—9 of Fig. 8; and

Fig. 10 is a transverse section on the line 10—10 of Fig. 8. 65

Before proceeding to a more detailed explanation of my invention, it should be understood that while the still is primarily intended for the production of pitch carbon from coal tar pitch, it can also be utilized 70 for other purposes to which devices of this kind are adapted. I prefer, especially in connection with the form of the still shown in Figs. 1 to 7, inclusive, to employ standard elements for the body of the still, such 75 as cast-iron, 90° pipe elbows. These may be of any suitable size, and may, for example, be 36 to 48 inches in diameter. I have found that cast-iron is particularly useful in the construction of stills of this kind, as it is not 80 subject to undue distortion incident to the high temperatures employed, as would be the case if the still were fashioned from riveted pieces or sheets of metal or the like.

Furthermore, in a still of this kind it is absolutely essential that joints and cracks no matter how closely joined or riveted, be obviated, for the material, while undergoing distillation, attains a high degree of fluidity, and can very readily escape through even 90 minute cracks or interstices. It is also desirable, as is accomplished in my still, to provide as great a surface for the action of heat, as possible.

It will be noted, furthermore, that by 95 means of the still of my invention the body of material undergoing distillation is of elongated form and decreases in width and depth from the center of the still to the ends, at which the outlets are located for the 100

removal of the residue, *i. e.*, the pitch carbon, after the distillation has been completed.

By maintaining the material in a comparatively shallow, narrow body, it is easy 5 to remove the pitch carbon by means of rakes or other suitable devices, as is customary, the removal being effected at both ends of the still.

Many of the details of construction illustrated and described, for example herewith, 10 form no part of the invention, and may be varied in accordance with individual preference or special conditions, without departing from the spirit of the invention.

15 Referring more particularly to the drawings, Figs. 1 to 7 inclusive, the body 10 of the still therein shown consists of a cast-iron, 90° pipe elbow or bend of suitable diameter. The body is normally open at each 20 end. It is disposed with its longer, rounded side downward, and its open ends directed upwardly. It is mounted over a suitable furnace or fire-box 11 having the usual brick walls 12 and a grate 13. The still body is 25 supported in any convenient manner, for example, by suitably shaped brackets 14, secured to the still body, near the ends thereof, by means of bolts or lag screws 15. The brackets are offset, to form shoulders 16 en- 30 gaging under the laterally disposed, annular flanges 17, at the ends of the elbow, and integral therewith.

Each end of the still is provided with a cover-plate 18, circular in form, and secured 35 by means of bolts 19, to the flanges 16. A suitable annular gasket 20 is interposed between the cover-plate and the flange 17 in each instance. Each cover-plate, near its upper edge, has an opening 21 to which is 40 fitted the flanged end 23 of a pipe 24, a suitable gasket 25 being interposed between the parts, to effect a tight joint. The pipe is secured in position by means of bolts or screws 26. One of the pipes 24 serves for 45 the introduction of the material to undergo distillation and the other pipe 24 serves for the escape of gaseous products of distillation, which are condensed and collected in the usual manner. The source of supply or 50 the means provided for the reception of the gaseous products form no part of the invention and are not shown.

Each cover-plate, near its lower edge has a larger opening 27, over which is fitted a 55 suitably formed and proportioned door plate 28. The opening and the door plate are of elongated, rounded form, and extend substantially across the width of the lower part of the cover-plate. The openings 27 serve 60 for the removal of the material after the distillation process has been completed. Any suitable means may be used for securely clamping the door plates over the openings,

to prevent the escape of gaseous products, during the progress of the distillation process. I have shown, for example, as used 65 for this purpose, a holder bar 29, the ends of which are movably received under offset lugs 30 and 31 of two brackets 32 and 33, secured by means of lag screws or bolts 34 70 to I-beams 35 of the flanges 17. The bracket 32 has an inwardly-directed extremity 36 under which one edge of the cover-plate is received. At the other end, the cover-plate has a finger 37 removably received in an 75 opening 38 of the bracket 33. Rotatably carried by the holder-bar 29 is a pressure screw 39 having a knurled head 40 by means of which it may be manipulated. The end of the screw engages the cover-plate and 80 serves to press the same firmly into position.

As is shown in Fig. 5, the upper surface of the body of the material undergoing distillation is of substantially elongated, rounded form. It will be readily understood 85 that it is comparatively shallow and is of decreasing depth from the center of the still to the ends. This shallow form of the body not only facilitates the distillation process but also renders easy the removal of the resultant pitch through the end openings of the still. In the form of still shown in Figs. 90 8 to 10 inclusive, the still body 41 consists of a lower section 42 and an upper section 43. The latter is of semi-cylindrical form. 95 The lower section approximately corresponds in form to the lower half of the body of the still already described.

In this case, too, the body is mounted upon the walls 44 of the fire-box or furnace, by 100 means of brackets 45. The upper and lower parts of the still body have laterally extending and similarly disposed flanges 46 and 47 secured together by means of bolts or the like, 48. Suitable gaskets 49 are interposed between the contacting surfaces. Each end of the still is closed by means of a cover-plate 50 seating against a gasket 51 and secured in place by means of bolts or the like, 52. Each cover-plate has an opening 105 53 into which is fitted the end of a pipe 54. These pipes 54 serve the same purposes as the pipes 24 of the preferred form of the still. Each cover-plate furthermore, has an outlet opening 55 closed by means of a door 110 plate 56 and secured in place by means of suitable mechanism 57, similar to that already described, or of any kind adapted for the purpose.

It will be understood that while this form 115 of the still differs somewhat from that of the preferred form, the body of the material undergoing distillation therein assumes the same shape as that in the other, with the same resultant advantages.

Having thus described my invention, I

claim as new, and desire to secure by Letters Patent:—

A still adapted for the distillation of pitch comprising a tubular, open ended body 5 circular in cross section and having an arcuate, longitudinal axis, the ends of said body being upwardly disposed so as to be above the normal level of the pitch, a clo-

sure rigidly secured to each end, an inlet pipe in one of said closures, an outlet vapor 10 pipe in the other of said closures, and a removable closure associated with each of the first mentioned closures adapted for the removal of residue from said still.

HAROLD PEARSON HIRD.
